TENT CABIN

Theron S. Castner, Minneapolis, Minn., assignor
to Nina C. Castner, Minneapolis, Minn.

Application April 18, 1934, Serial No. 721,199

10 Claims. (Cl. 135—1)

This invention relates to knock-down, portable building structures and it relates more particularly to tent cabins, which can be quickly set up and moved from place to place, if desired.

6 It is the general object of this invention to provide a novel, inexpensive, knock-down tent cabin, which can be quickly erected with ease, which can be stored in small compass and which can be readily transported from one point to another.

More specifically it is an object of the invention to provide a tent cabin including walls made from a multiplicity of sections, readily attachable means for holding the sections together and a 15 fabric roof supported in tautly stretched condition over the walls and from the walls without use of rafters.

To these ends, generally stated, the invention consists in the novel parts and novel combinations of parts hereinafter defined in the claims and described in the following specification, made in connection with the accompanying drawings, wherein like reference characters refer to the the same or similar parts throughout the various 25 views, and, in which,

Fig. 1 is a view partly in front elevation and partly in vertical section illustrating a tent cabin embodying the invention;

Fig. 2 is a plan view of the same, portions of 30 the roof being broken away and the jack being shown in section to more clearly illustrate other parts of the tent cabin;

Fig. 3 is a vertical section taken on the line 3—3 of Fig. 2, as indicated by the arrows;

Fig. 4 is a vertical section taken on the line 4—4 of Fig. 3, as indicated by the arrows;

Fig. 5 is a partial vertical section taken on the line 5—5 of Fig. 1, as indicated by the arrows;

Fig. 6 is a plan view showing in detail a corner 40 of the tent cabin, the roof being removed;

Fig. 7 is a broken plan view illustrating a modified form of yoke that may be used;

Fig. 8 is a vertical section taken on the line 8—8 of Fig. 7, as indicated by the arrows; and

Fig. 9 is a section taken on the line 9—9 of Fig. 7, as indicated by the arrows.

Referring first to the embodiment of the invention illustrated in Figs. 1 to 6, there are provided a multiplicity of rectangular building sections 50 10, which are vertically disposed at the four sides of a rectangle with the edges of adjacent sections in abutment to form the side walls of a building structure. These various sections 10, in the illustrated embodiment, each includes a rectangular frame 10a, the side rails of which are

connected intermediate the ends thereof by a cross bar 10b. A panel 10c fills the space from the cross bar 10b between the side rails downwardly to the lower cross piece of the frame, while screening 10d covers the rectangular space 55 formed between the two side rails from the cross bar 10b upwardly to the top cross piece of the frame. It will of course be understood that within the scope of the invention, panels may be substituted for the screens 10d or screens may be 10 substituted for the panels 10c, or the detailed construction of the sections 10 may be otherwise varied as desired. One or more of the sections 10, distinguished from its fellows by the numeral 10', may be utilized as a door and this section 10' is connected by hinges 11 to one edge of an adjacent section 10 in such manner that the door 10' may swing inwardly.

The various sections 10 forming the various sides of the structure are held in assembled relation by means of lower bars 12 and upper bars 13 removably secured as by bolts 14 to the respective lower and upper edges of the various sections 10 at the outer sides thereof. Of course the bars 12 and 13 will have no connection with 20 the door section 10'. The upper bars 13 have rounded outer edges, as best shown in Fig. 3, for a purpose presently to appear.

Diagonal corner brackets 15 are secured to the inner surfaces of the upper and lower edges of 30 the sections 10 forming the corners of the structure, and these brackets as shown may be conveniently formed from channel iron having projecting tongues attached to the corner sections 10. Centrally located relative to the four upper 35 corner brackets 15 is a yoke 16 which, in the present embodiment, is of ellipse-shape and is constructed of channel iron disposed so that the central web of the channel iron is inwardly disposed and the flanges of the channel iron project 40 outwardly. A turnbuckle 17 having eyes formed at the two ends of the screw rods is positioned within the yoke 16 and V-shaped flexible cables 18 connected at their ends respectively, to the upper corner brackets 15 at corresponding ends 45 of the structure project through slots 16a formed in the central web of the yoke 16 and these cables also extend through the eyes formed on the screw rods of the turnbuckle 17. The lengths of the 50 cables 18 are adjustable and for this purpose the cables near their outer ends are passed through openings in the upper corner brackets 15 and clamping blocks 19 are connected to the end portions of the cables to bear against the outer surfaces of the brackets 15. The slots 16a are quite 55

wide so as to permit the central portions of the cables 18 to move longitudinally of the yoke 16 without bending the cables as the turnbuckle 17 is adjusted. Brace rods 20 preventing the walls 5 formed by the sections 10 from buckling as the turnbuckle 17 is drawn up, are provided, and these rods 20 bear at their inner ends against the intermediate web of the yoke 16 and they bear at their outer ends against the upper portions of certain 10 of the sections 10 forming parts of the various walls of the structure. The rods 20 are releasably connected at their ends to the yoke 16 and to the sections 10 against which they bear in any suitable manner. In the illustrated embodiment, 15 the outer ends of the rods 20 are provided with caps 21 screwed onto these ends and bolts 22 run through the caps, the particular sections 10 and the bars 13. At their inner ends the brace rods 18 are held in place on the yoke 16 by means of 20 nutted bolts 23.

Extending transversely of the yoke 16 and connected thereto is a jack support 24 of arch-shape and preferably of channel construction having its intermediate web lowermost and its side flanges 25 upwardly disposed. Connected to a central hub formed on the jack support 24 is an upwardly extending jack which in the illustrated embodiment consists of a turnbuckle 25, one screw rod of which is attached to the said hub and the other screw rod of which is connected to a pipe 30 26 connected to a T-fitting 27, the said T-fitting carrying pipes 28 which project toward the end walls of the structure and have downwardly curved end portions.

35 A rectangular frame 29 formed of rods or pipe connected by pipe fittings encircles the walls of the structure near the upper portions thereof in outwardly spaced relation therefrom, and this frame is suitably supported from the lower bars 40 12 as by means of diagonal supporting rods or pipes 30 which are connected at their upper ends to the frame 29 and are flattened at their lower ends and are secured at their lower ends to the bars 12 as by certain of the bolts 14.

45 A pitched roof 31 for the structure is formed from canvas or other strong, flexible fabric and this roof has a reinforcing strip 32 secured to its central portion at its under side which overlies and rests on the pipes 28 of the jack. The 50 various edges of the roof 31 project beyond the upper edges of the walls formed by the sections 10 and are formed with elongated tubular pockets 31a within which the rods of the frame 29 are 55 removably secured. Secured to the roof canvas 31 immediately above the upper edges of the walls of the structure, are long strips 33 preferably 60 stitched at their upper edges to the roof canvas and hanging downwardly to form flaps. At spaced points longitudinally of these strips 33, short straps 34 equipped with buckles 35 are 65 provided and the straps 34 are attached to the outer surfaces of the flaps. For cooperation with the buckles 35 straps 36 are provided and these straps 36 are attached at their lower ends to the lower outer edges of the upper bars 13 and they are, of course, provided with a number of 70 openings for engagement with the buckles 35.

In erecting the structure the lower and upper 75 bars 12 and 13 will first be secured by the bolts 14 to the various sections 10 forming the different sides of the structure. The walls will then be raised vertically and the corner brackets 15 will be attached. Cables 18 running through the slots 16a of the yoke 16 and also passing through the eyes of the turnbuckle 17 will then be secured

to the upper corner brackets 15 and the struts formed by the brace rods 20 will be attached. The turnbuckle 17 will then be tightly drawn up to tension the cables 18, thereby causing the corners of the wall structure to be drawn inwardly toward the center of the structure, the brace rods 20 acting to prevent the walls from buckling as the cables 18 are tightened. The jack formed by the turnbuckle 25, pipe 26, fitting 27 and pipes 28 will, of course, be erected on the jack base 24 10 and the various rods of the frame 29 will be carried through the tubular pockets 31a of the canvas roof 31 whereupon the frame 29 can be completely assembled. The canvas roof 31 having its edges attached to the frame 29 may then be 15 carried over the walled structure whereupon the supporting rods 30 may be engaged with the frame 29 and attached at their lower ends to the lower bars 12. The straps 36 will then be engaged with the buckles 34 and pulled downwardly to 20 cause the various flaps of the strips 33 to tightly engage the upper edges of the upper bars 13. Finally the turnbuckle 25 can be operated to raise the jack of which the turnbuckle forms a 25 part and thereby stretch the canvas roof 31 taut.

It will be seen that the canvas roof is supported from the side walls of the structure through the medium of the jack, the yoke 16, the turnbuckle 17, the cables 18 and the upper corner brackets 15. No central pole for supporting the 30 canvas roof is necessary and no rafters are needed for supporting the roof. The yoke 16, cables 18, turnbuckle 17, brace rods 20 and the jack tie the various parts together and brace the various parts in exceedingly simple manner. 35 The entire structure can be erected in a very short period of time and it can be disassembled as quickly. The various parts are light and can be stored away in small compass when not in use or they can be transported from one site to 40 another readily.

The width and length of the structure can be easily varied by utilizing more or less of the sections 10 to form the side and end walls. It will be appreciated that the structure of the yoke 45 16 can be varied considerably to permit utilization of any number of brace rods 20 and to permit the use of any number of jacks similar to that illustrated.

In Figs. 7, 8 and 9, a slightly modified type 50 of structure for tying together and bracing the parts is shown to take the place of the yoke 16, turnbuckle 17, cables 18, jack base 24 and brace rods 20. Referring to Figs. 7, 8 and 9, a yoke 37 is provided which consists of two parallel spaced 55 channel irons 37a secured together in spaced relation by means of blocks 37b. Near the ends of the yoke, sheaves 38 are located between the two bars 37a, these sheaves being mounted for rotation on pivots 39 attached to the two bars. Cables 60 40 attached at their outer ends to the corner bracket 15 extend between the two bars 37a of the yoke and run over the sheaves 38. Each of the cables 40 is made in two sections, the two sections of which are connected together by 65 means of turnbuckles 41. Brace rods 42 corresponding to the brace rods 20 are connected to the sides and the ends of the yoke 37. Jacks 43 corresponding to the jacks previously described 70 are mounted preferably near the two ends of the yoke 37 in upstanding relation and these two jacks will support a pipe or rod corresponding to the ridge support formed by the pipes 28 or, if desired, the jacks alone can be used. With the 75

structure shown in Figs. 7, 8 and 9, each cable 40 is individually tightened by its turnbuckle 41.

Although the tent cabin of the invention is particularly adapted for use in warm climates or as an auxiliary cottage or outing cabin for summer use, it can be utilized for many other purposes, such for example as a garage, a shed, a storehouse, etc.

It will, of course, be understood that various changes may be made in the form, details, arrangement and proportions of the various parts without departure from the scope of the present invention.

What is claimed is:—

1. A knock down tent cabin, having in combination a multiplicity of rectangular building sections assembled together in juxtaposition to form four vertical joining walls, bars holding said sections at top and bottom assembled in such relation, a pitched fabric roof overlying said walls and means supported from the upper corners of said four walls and in turn supporting the central portion of said roof without use of rafters.

2. A tent cabin having in combination four vertical walls disposed at the sides of a rectangle, a pitched fabric roof overlying said walls, flap strips of flexible material attached at their upper edges to said roof above and adjacent the upper edges of said walls, straps connecting said flap strips to the upper edges of said walls and tightly holding said strips against the upper edges of said walls and means for supporting the central part of said roof.

3. A tent cabin comprising four vertical walls disposed at the sides of a rectangle, a yoke centrally disposed relative to said walls, cables connected to the corners of said walls and supporting said yoke, a jack supported from said yoke, a pitched fabric roof centrally supported by said jack and overlying said walls and means for anchoring the edges of said roof.

4. A tent cabin comprising four vertical walls disposed at the sides of a rectangle, a yoke centrally disposed relative to said walls, cables connected to the corners of said walls and running through said yoke, means for tightening said cables, a jack supported from said yoke, a fabric roof centrally supported by said jack and overlying said walls and means for anchoring the edges of said roof.

5. The structure defined in claim 4, and braces extending from said yoke to the upper portions of said walls.

6. A tent cabin comprising four vertical walls disposed at the sides of a rectangle and connected together, a yoke centrally disposed relative to said walls, a pair of cables connected respectively at their ends to the upper corners of opposing walls and having central portions extending through

said yoke, said yoke having slots receiving the central portions of said cables, a tightening device connecting the central portions of said two cables, a jack supported by said yoke, a fabric roof supported at its center by said jack and overlying said walls and means for anchoring the edges of said roof.

7. A tent cabin comprising four vertical walls disposed at the sides of a rectangle and connected together, a yoke centrally disposed relative to 10 said walls, sheaves carried at the ends of said yoke, a pair of cables connected respectively at their ends to the upper corners of opposing walls and having central portions running over said sheaves, means for tightening said cables, a jack 15 supported by said yoke, a fabric roof supported at its center by said jack and overlying said walls and means for anchoring the edges of said roof.

8. A tent cabin comprising in combination a multiplicity of rectangular building sections disposed vertically at the sides of a rectangle to form four joining walls, upper and lower bars connecting together the upper and lower edges of the sections forming the various walls, said bars being disposed at the outer sides of said sections and the upper bars having rounded outer edges, a fabric roof overlying said walls, means for supporting said roof at its central portion, flap strips of flexible material attached to said roof above and adjacent the upper edges of said walls 30 and interengaging straps connected respectively to said strips and to said upper bars for drawing said strips into tight engagement with the upper edges of said upper bars and holding the same.

9. A knock down tent cabin comprising in combination a plurality of rectangular building sections, said sections being set up vertically to form four walls disposed at the sides of a rectangle, upper and lower bars connecting the sections forming the respective walls, a yoke centrally disposed relative to said walls, braces extending between said yoke and said walls, cables connected to the upper corners formed by said wall and passing through said yoke, means for tightening said cables, a jack supported by said yoke and 45 projecting above the same, a fabric roof centrally supported by said jack, overlying said walls and having edges projecting beyond said walls, a rectangular frame connected to the edges of said roof and supports for said frame.

10. The structure defined in claim 9, flap strips connected at their upper edges to said roof over but adjacent the upper edges of said walls and cooperating fastening devices connected to said flap strips and said upper bars for drawing the 55 lower edges of said flap strips into engagement with the upper edges of said upper bars and securing the strips in this relation.

HERON S. CASTNER.
